ELECTRIC MEDICINAL VAPORIZER

Daniel Tauben, Paterson, N. J.

Application October 20, 1955, Serial No. 38,492

Term of patent 14 years

(Cl. D83—1)

Fig. 1

Fig. 2

Figure 1 is a perspective view of an electric medicinal vaporizer showing my new design; and

Figure 2 is a side elevational view of the same.

I claim:

The ornamental design for an electric medicinal vaporizer, as shown.
